SMOKE INDICATOR DEVICE

Henry Thomas, Elizabeth, N. J.

Application March 6, 1939, Serial No. 260,011

6 Claims. (Cl. 88—14)

This invention relates to smoke detector or indicator devices and more particularly to an improved method and means for calibrating and adjusting the same.

One of the objects of the present invention is to provide a simple and effective calibrating and adjusting means for said devices. Another object is to provide such a means which is operative by one unskilled in the art. Still another object is to improve the operating efficiency of smoke detector and indicator devices. Other objects and advantages will be apparent as the invention is more fully disclosed.

Smoke detector or indicator devices are utilized in the art as a means for controlling the combustion conditions within a furnace or fire box whereby more efficient combustion of the fuel input to the furnace or fire box is obtained. In general such devices comprise a radiation sensitive means, a source of radiation and means to mount the radiation sensitive means and the source of radiation adjacent aligned openings in opposite sides of a smoke flue or chimney in such manner that the radiation from the source will be projected through the openings onto the radiation sensitive means. The radiation sensitive means is connected in an electrical circuit to operate an electro-responsive means such as a recorder device, an indicator device, an alarm system or means automatically regulating the fuel and air input to the furnace or fire box or any combination of these instrumentalities, as may be desired, the said electrical circuit usually including an adjustable means limiting energization of any control means associated therewith to determined maximum and minimum limits of current intensities in the said circuit.

It is essential in such an arrangement to maintain a substantially constant voltage on the source of radiation and in the circuit including the radiation sensitive means to obtain uniformly constant operation of the arrangement. It is also customary to provide air vent openings between the radiation sensitive means and the flue and between the source of radiation and the flue to prevent the passage of smoke dust and condensation products into the housing inclosing the radiation sensitive means and the source of radiation thereby to prevent the deposit of dust and condensation products on the lens means utilized with the radiation sensitive means and the source of radiation to transmit radiation in beam form from the source of radiation (normally a lamp) to the radiation sensitive means (normally a photo-sensitive device). Such dust

and condensation products by clouding up the lens means alter the operating characteristics of the said devices.

In operation, smoke detector devices record or indicate the loss of radiation incident to the density of the gases passing through the flue. With a perfectly clear flue, as when no combustion gases are circulating through the flue, the radiation sensitive means receives and is actuated by the maximum radiation from the source of radiation. As the amount of smoke and gases of combustion increases the amount of radiation received by the radiation sensitive means decreases. Under any given furnace or fire box conditions and with any given fuel, substantially perfect combustion of the fuel produces a determined flue gas density. It is possible to measure the carbon dioxide (CO₂) content of the flue gases and to so correlate the radiation sensitive device readings with the carbon dioxide content that with any given reading a known carbon dioxide content is indicated.

The carbon dioxide content of any flue gas is representative of the combustion conditions and in general it is desired to maintain a carbon dioxide content of between 12 and 15% in the flue gases as within this range substantially perfect combustion conditions are maintained.

Most smoke indicator or detector devices are provided therefore with means to record or to visually indicate when the density of the flue gases rises or falls above or below this range and for any given installation require frequent calibration, *in situ*, against a gas analysis device.

Such calibration requires the services of an expert operator and the use of special gas analysis equipment and the expense involved is prohibitive for small installations.

The present invention provides a simple and effective means to obtain the calibration of smoke indicator devices to within any desired range of smoke densities representative of any desired CO₂ content in the flue gases, and also provides means to rapidly calibrate and adjust a smoke indicator device which does not require the services of an expert operator or the use of special gas analysis equipment.

In accordance with the objects of this invention I have devised a calibrating means which consists of a plurality of plates or sections, preferably but not necessarily assembled together substantially as shown in the drawing, each plate being comprised of suitable material having a translucency or opacity adapted to intercept a determined portion or percentage of light radi-

ation in the beam being projected from the light source, the size, shape and configuration of the plate or section preferably being such that it may be readily inserted in position across the path of travel of the beam of radiation projected from the source to the radiation sensitive means to intercept the same before reaching the said radiation sensitive means.

By previous calibration of these said plates or sections in a laboratory or other location under known conditions, each said plate or section may be identified as being representative of a known or determined smoke density and as being representative of a known or determined carbon dioxide percentage.

By utilizing this invention, the furnace operator before starting up the furnace or fire box has only to decide within which range of smoke density or carbon dioxide percentages furnace operation is desired and to adjust his indicator device to this range by the insertion of the required plates in position for a sufficient time interval to set the indicator device to operate within the desired range. Subsequent furnace operation will be regulated in accordance with the settings thereby obtained.

In the drawing, Fig. 1 illustrates in section a typical installation of smoke indicator device; Fig. 2 is a side elevational view, partly in section; Fig. 3 illustrates one specific embodiment of the present invention; Fig. 4 illustrates a second specific embodiment; and Fig. 5 illustrates a third specific embodiment of the same.

Referring to the drawing, Fig. 1, a typical installation of a smoke indicator device comprises a source S of radiation, a radiation sensitive device R and means substantially as indicated to sustain the source S and device R adjacent aligned openings O—O' in opposite side walls of flue F but in spaced relation to the side walls so that air vent openings A—A' are provided to prevent smoke dust and condensates from passing from the flue into said devices S and R. The specific structure of devices S and R forms no part of the present invention and accordingly, being well known in the art, need not be specifically described. However, in Fig. 1 I have shown diagrammatically a lamp B and a lens C and in Fig. 2 I have shown diagrammatically a lens D and a radiation sensitive device E for purposes of illustration. The radiation sensitive device E is electrically connected in an electrical circuit 18 energized by current from source 14 including an electro-responsive device such as visual indicator 11 and an adjustable means 12 for controlling the energization of external electric control circuits 13a—13b at determined maximum and minimum intensities of the electrical current flowing in circuit 18. The precise arrangement of the elements comprising the means 10, 11, 12, 13a—13b and 14, forms no part of the present invention and is well known in the art and accordingly need not be more specifically described.

In accordance with the present invention, the intensity of the beam of radiation L passing from source S to device R is altered a determined degree by interposing plate P, preferably in the air vent opening adjacent the radiation sensitive device R but alternatively and with equally good results plate P may be disposed within the air vent opening adjacent the source S, if desired. Plate P essentially comprises a material of known or determined density or translucency adapted to intercept a known or determined per-

centage of the radiation L representative of that intercepted by flue gases of equivalent density and of known or calibrated carbon dioxide content indicative of a determined combustion condition within the furnace or fire box connected with the flue.

As illustrated in Fig. 3, the plate P may be comprised of a plurality of sections 1 to 5 inclusive, each section having a different density or translucency. Plate P, for example, may be comprised of glass having one surface frosted, the degree of frosting on each section varying a determined amount to give a desired range of densities. Alternatively, the glass plate P may be smoked or otherwise colored exteriorly or interiorly to obtain this same result. As a third alternative, the translucency of the glass may be altered by incorporating therein any desired opaques material to obtain the same result.

As a second specific embodiment (Fig. 4), plate P' may be comprised of screen material, the screen mesh being varied in each section 1—5 to obtain the desired range of percentage of radiation interruption, substantially as indicated.

As a third specific embodiment (Fig. 5) the plate P'' may be comprised of perforated strip material with the number of perforations varying in each section 1—5 to obtain a desired range of percentage of radiation interruption, substantially as indicated.

It is believed apparent that the density of each section 1—5 of plate P, P' and P'' may be calibrated with respect to an equivalent density of flue gases causing an equivalent interruption of radiation and with respect to the known carbon dioxide content of such gases and may be standardized in this respect under laboratory control conditions with any given fuel supply to the furnace or fire box, such as oil, coal, pulverized fuel etc., and when so calibrated and standardized may be employed as a substitute for more expensive and intricate methods of calibration now in use. In small unit installations this is a marked advantage.

Having broadly and specifically disclosed the present invention and given three specific embodiments of the same, it is apparent that many modifications and adaptations of the same may be made without essential departure therefrom and all such modifications and adaptations are contemplated as may fall within the scope of the accompanying claims.

What I claim is:

1. In smoke indicator devices comprising a radiation sensitive means, a source of radiation of substantially constant intensity, means sustaining the said radiation sensitive means and the said source of radiation adjacent aligned openings in opposite sides of a smoke flue and an electrical circuit including said radiation sensitive means, a source of electrical energy, and an adjustable means for controlling the energization of external electric control circuits at determined maximum and minimum limits of current intensities in said electrical circuit, the method of obtaining desired adjustment of said adjustable means which comprises reducing the intensity of the beam of radiation falling on said radiation sensitive device to that approximating the intensity produced by the maximum permissible smoke density in the flue, adjusting the said adjustable means to be actuated by the electrical energy thereby induced in said radiation sensitive device, reducing the intensity of said beam of radiation falling on the said radiation

sensitive device to that approximating the intensity produced by the minimum permissible smoke density in the flue and adjusting the said adjustable means to be actuated by the electrical energy thereby induced in the said radiation sensitive device, and then restoring the intensity of the said beam of radiation to its original intensity and maintaining the same substantially constant during the passage of smoke gases through the said flue.

2. The method of claim 1 wherein the reduction of the intensity of said beam of radiation to the maximum and minimum intensities respectively is obtained by inserting in radiation interrupting position between the radiation sensitive device and said source of radiation at least two radiation permeable members having respectively a density approximating the permissible maximum and minimum densities of the column of smoke normally present in said flue.

3. The method of claim 1 wherein the reduction of the intensity of said beam of radiation to the maximum and minimum intensities respectively is obtained by inserting in radiation interrupting position between the radiation sensitive device and the said source of radiation, a radiation permeable member comprised of glass, the density and radiation absorbing properties of said glass approximating that representative of the column of smoke in said flue at maximum and minimum densities respectively.

4. The method of claim 1 wherein the reduction of the intensity of said beam of radiation is made to be that representative of desired maximum and minimum CO₂ contents in the smoke gases traversing the said flue.

5. In combination with a smoke detector device including a radiation emitting device and a radiation sensitive device and means sustaining the two said devices opposite aligned openings in a flue with the said radiation sensitive device electrically connected in an electric circuit including a source of electrical energy and an adjustable means for controlling the energization of external electric control circuits at determined maximum and minimum limits of current intensities in said electrical circuit, a means to obtain

- 15 a predetermined setting of said adjustable means, said means comprising a plurality of filter members each of a different radiation interrupting characteristic with the plurality of said filter members comprising a graduated range of radiation interrupting characteristics representative of determined smoke densities and CO₂ content ranges and covering the range of adjustment of said adjustable means and means to position said members successively in radiation interrupting position between said radiation sensitive device and said radiation emitting device thereby to artificially induce in said radiation sensitive device the electrical response representative of the degree of radiation interruption characteristic of the said member.
- 20 6. In combination with a smoke detector device including a source of radiation, a radiation sensitive device disposed relative to said source of radiation to be energized thereby, means to pass continuously a column of smoke in radiation interrupting position between said radiation sensitive device and said source of radiation, and an electrical circuit including said radiation sensitive device, a source of electrical energy and an adjustable means for controlling the energization of external electric control circuits at determined maximum and minimum current intensities in said electrical circuit, means to obtain a presetting of said adjustable means to maximum and minimum settings representative of desired maximum and minimum smoke densities, said means comprising a plurality of radiation permeable members each with a different and known density approximating that of the column of smoke at different CO₂ contents, the plurality of members covering a range of smoke densities, and means to dispose any one of said members in radiation interrupting position between the radiation sensitive device and the said source of radiation in place of said smoke column to simulate in said radiation sensitive device an electric current intensity representative thereof for a time interval at least sufficient to obtain an adjustment of said adjustable means.

HENRY THOMAS.
